DESIGN FOR A PLATEN FRAME FOR TYPE-WRITING MACHINES

Jacob N. Hoffman, Bridgeport, Conn., assignor to Underwood Elliott Fisher Company, New York, N. Y., a corporation of Delaware

Application June 18, 1937, Serial No. 69,896

Term of patent 7 years

To all whom it may concern:

Be it known that I, Jacob N. Hoffman, a citizen of the United States of America, residing at Bridgeport, Fairfield County, Connecticut, have invented a new, original, and ornamental Design for a Platen Frame for Typewriting Machines, of which the following is a specification, reference being had to the accompanying drawing, forming part thereof.

Fig. 1 is a perspective view of a platen frame for typewriting machines, showing my new design, and Fig. 2 is a view in side elevation thereof.

I claim:

The ornamental design for a platen frame for typewriting machines, as shown.

JACOB N. HOFFMAN.
